UNITED STATES PATENT OFFICE.

CHARLES W. LOGAN, OF KENMORE, NEW YORK, ASSIGNOR TO MARKEL ELECTRIC PRODUCTS, INC., OF BUFFALO, NEW YORK, A CORPORATION OF NEW YORK.

DESIGN FOR A WALL FIXTURE FOR ELECTRIC LIGHTS.

Application filed November 23, 1928. Serial No. 29,021. Term of patent 3½ years.

To all whom it may concern:

Be it known that I, CHARLES W. LOGAN, a citizen of the United States, residing at Kenmore, in the county of Erie and State of New York, have invented a new, original, and ornamental Design for a Wall Fixture for Electric Lights, of which the following is a specification, reference being had to the accompanying drawing, forming part thereof.

In said drawing:

Figure 1 is an elevation of a wall fixture for

electric lights embodying my new design. In this figure half of the fixture with the applied ornamentation is shown in full lines and the remaining half in dot and dash lines.

Figure 2 is a top plan view of the same, similarly executed in full and dot and dash lines.

I claim:

The ornamental design for a wall fixture for electric lights, substantially as shown.

CHARLES W. LOGAN.
